UNITED STATES PATENT OFFICE.

EMIL TYDEN, OF EVANSTON, ILLINOIS.

SEAL-LOCK.

1,115,620.

Specification of Letters Patent.

Patented Nov. 3, 1914.

Application filed May 13, 1914. Serial No. 838,207.

To all whom it may concern:

Be it known that I, EMIL TYDEN, a citizen of the United States, residing at Evanston, in the county of Cook and State of Illinois, have invented new and useful Improvements in Seal-Locks, of which the following is a specification, reference being had to the accompanying drawings, forming a part thereof.

10 The purpose of this invention is to provide an improved seal locking device, particularly adapted for securing telescoped members such as a can body and its telescoped cover, or a box and its lid which shuts into the box.

15 It consists in the elements and features of construction shown and described, as indicated in the claims.

20 In the drawings, the invention is shown as applied to a can having a telescoping cover.

Figure 1 is a vertical section of a portion of a can body and cover and a seal-locking device embodying this invention, applied thereto. Fig. 2 is a top plan view of the 25 seal mount and seal therein detached from the can. Fig. 3 is a plan view of the blanks from which the seal bolt is made by doubling it upon itself at a line indicated. Fig. 4 is a view similar to Fig. 1, showing a modified 30 form of the invention. Fig. 5 is an inverted plan view of the form shown in Fig. 4. Fig. 6 is a plan view of the seal bolt for the device shown in Figs. 4 and 5. Fig. 7 is a view similar to Fig. 1 showing a modified form 35 of the device. Fig. 8 is a section at the line 8-8 on Fig. 7. Fig. 9 is a plan view of the seal bolt suitable for use in the form of the device shown in Fig. 7.

40 In the drawings, 1 represents a portion of a can body; 2 is the cover for the same telescoped therewith. The cover has on its telescoped portion an exterior circumferential groove, 2^a, for engagement of the seal bolt. Upon the outside of the neck of the can body 45 there is secured the seal mount, 3, which is a bracket-like device riveted to the can neck, comprising a web, 3^a, and two up-raises therefrom, 3^b and 3^c, each having a seal aperture, the aperture, 3^d, in the up-raise, 3^b, is that 50 through which the seal bolt thrusts for locking, and the can body has an aperture, 1^a, registering with said aperture, 3^d, in position for registering with the groove, 2^a, of the cover when the cover is in closed position. 55 The aperture, 3^e, is extended down through the web, 3^a, being made at the junction of

the web and up-raise, 3^c, and cut down through the former as well as out through the latter. The seal bolt for coöperating with this mount is a strip 5, doubled upon itself at the line, 5^a, the lower ply being extended farther than the upper ply, and having its end remote from the fold adapted to serve as a bolt to engage the groove, 2^a, of the cover. The upper ply, 5^b, is weakened 65 at a transverse line which when the seal bolt is in locking position shown in Fig. 1, stands adjacent the inner side of the up-raise, 3^c, such weakening being most conveniently effected by cutting a transverse slot, 5^c, in 70 said ply, 5^b. The end portion of this ply beyond the slot, 5^c, is designed to receive, and is shown as bearing, an identifying mark, and is preferably up-bent, as seen in 75 Fig. 1, for the purpose of convenience in taking hold of this ply for folding it to secure it, as will be explained.

80 The can having been closed by telescoping the cover with the body to the proper position, the seal folded as described is inserted, folded end first, through the aperture, 3^d, far enough to permit the remote end of the lower ply to pass down along the inner up-raise, 3^b, to the aperture, 3^d, therein, and is then thrust inward through said aperture, 85 engaging the slot, 2^a. The operator now taking hold of the up-bent end of the upper ply will bend it at the weakened line of the slot, 5^c, over the up-raise, 3^c, to the position shown in dotted line in Fig. 1. The identifying 90 mark on the end portion of the seal thus bent over, is made to read from the side which is exposed uppermost when it is thus bent, which is the under or inner side when the seal is folded before use. It is now impossible to disengage the seal bolt for opening the can without bending back the marked end of the seal bolt to its original position, and in such bending it will break by reason of weakening at the slot, 5^c. It might be 95 possible, however, to bend up the portion of the lower ply of the seal between the two up-raises, 3^b and 3^c, sufficiently to disengage the bolt end of the same from the groove, 2^a, of the can cover; and to prevent this being 100 done without breaking the seal and so disclosing the tampering, the lower ply is weakened at a point which, when it is engaged for locking as described, stands intermediate the two up-raises. This is most conveniently 110 done by cutting two notches, 5^e and 5^f, into the opposite edges at the point indicated.

In the form shown in Figs. 4, 5 and 6, the seal mount, 10, is a bracket riveted to the side of the can neck as in the other form, but having the seal seat on the under side of 5 a horizontal web, 11, and bounded by two vertically-depending flanges, 12, 12. A flat lug, 13, projects from the upper side of the web at the outer end. Projecting downward from the web midway in the wedge of the 10 seal-seat, there is a hook-lug, 14, having its hook end projecting toward the aperture, 15, through which the seal projects for locking. The seal in this form of the device is a strip, 16, having a slot, 17, for receiving the hook 15 lug, 14, and another slot, 18, for receiving the flat lug or nose-piece, 13; and it is weakened for breaking at one end of the slot, 18, by a cross slot, 19, which opens into the slot, 18, making the total opening T-shaped. The 20 end portion of the seal beyond the slot, 18, is designed to receive the identifying mark, and the opposite end is the bolt end for thrusting through the aperture, 15.

The proportions of the seal and mount are 25 such that for applying the seal and locking, the bolt end, 20, is inserted in the aperture, 15, and thrust there-through far enough to permit the aperture, 17, to receive the hook lug, 14, by swinging the seal up flat-wise. 30 against the under side of the web, 11. When thus applied, the bolt end, 20, projects through the aperture, 15, farther than necessary for locking the can cover, and may be withdrawn a little distance, and this being 35 done, the hook end of the lug, 14, engages the inner end of the aperture, 17, preventing the seal from being swung down again without being first thrust longitudinally. The distance of the slot, 19, from the slot, 17, 40 with respect to the distance of the neck of the hooked lug, 14, from the end of the bracket, is such that it is necessary to thus withdraw the seal so as to engage it with the hook, 14, in order to fold the seal at the slot, 45 19, up around the end of the bracket to pass the nose or lug, 13, through the slot, 18; and the length of the slot, 18, is such that the seal being thus folded, the lug, 13, fully occupies the slot, preventing any endwise movement 50 of the seal. The seal being weakened by the slot, 19, as described, will fold sharply when bent by hand, and being thus folded, it will be seen that the seal cannot be withdrawn in any direction unless the seal is unfolded at 55 the slot, 19, because so long as the end portion beyond the slot, 19, projects transversely of the end of the bracket, the seal cannot be pushed longitudinally inward to disengage it from the hook, 14, and until it is 60 thus disengaged it cannot be dropped down so as to pull it out of the aperture, 15. The weakening of the seal at the slot, 19, is such that, having been once folded to locking and securing position, as shown in dotted line in 65 Fig. 4, it cannot be straightened out so as to

be slid longitudinally to disengage it from the hook, 14, and until it can be thus slid longitudinally, it cannot be dropped down so as to be drawn back out of the aperture, 15, and therefore it is impossible to disengage 70 the seal without first breaking off the label end which is the purpose of the construction.

Fig. 7 illustrates a third modification of the invention in which the seal, 21, is bent back upon itself at 22, somewhat as in the 75 first form, but is inserted directly in the mount, 23, being passed under the upraise or abutment, 24, over the web, 25, and through the aperture, 1^a, in the neck of the can. The lower ply, 21, which serves as the bolt is 80 longer than the upper ply, 21^b, of the seal and is weakened by a transverse slot, 21^c, which registers with the edge of the web, 25, when the bolt end is inserted in locking position. In this position the outer folded end, 22, extends beyond the abutment, 24, of the 85 mount so that it may be grasped and swung downward, folding the lower ply of the seal about the line of weakness at 21^c; as the upper ply, 21^b, projects inward beyond this line 90 this projecting portion will thus be swung up away from the lower ply, 21^a, and back against the abutment, 24, serving as a stop to prevent withdrawal of the seal from the aperture, 1^a. To defeat the possibility of 95 raising the seal off the web, 25, and withdrawing it obliquely upward past the abutment, 24, the skirt, 26, of the mount, 23, is provided with a flange, 26^a, curved circularly 100 about the edge of the web, 25, over which the seal is folded. Both plies of the seal strip are notched at 21^d, for engagement with this flange, 26^a, through the entire range of the folding movement, so that before the seal 105 can be removed from the aperture, 1^a, it must be folded back over this curved path to the straight position illustrated in full lines in Fig. 7, but such folding would certainly result in breakage at the line of weakness at 21^c. Since the notch, 21^d, is much wider 110 than the thickness of the flange, 26^a, the broken-off portion of the seal will immediately drop down out of place and the absence of the portion, 21^b, from its proper position 115 (in contact with the abutment, 24) would give warning to an inspector that the lock had been tampered with.

I claim:

1. In combination with a seal mount having an aperture, a seal comprising a strip 120 having one end adapted to be thrust through said aperture in locking position, the mount having also an abutment facing the said aperture, the outer end of the seal strip being folded back toward the inner end 125 which occupies the aperture, and the portion of said strip between such fold and the outer end engaging the abutment of the mount to prevent withdrawal of the strip from the aperture, 130

2. In combination with a seal mount having an aperture, a seal comprising a strip having one end adapted to be thrust through said aperture in locking position, the mount 5 having also an abutment facing the said aperture, the seal strip being folded to bring its outer end portion into engagement with the abutment for preventing withdrawal of the inner end from the aperture, and said 10 strip being weakened at the line of such fold to insure breakage when unfolded for disengagement from the abutment.

3. In combination with a seal mount having an aperture, a seal comprising a strip 15 having one end adapted to be thrust through said aperture in locking position, the mount having also an abutment facing the said aperture, the outer end portion of the seal being formed as a stop engaging the said 20 abutment to prevent withdrawal of the strip from the aperture and the portion of the strip between the aperture and the abutment being weakened to insure breakage of such portion if bent.

25 4. In combination with a seal mount having an aperture, a seal comprising a strip having one end adapted to be thrust through said aperture in locking position, the mount having also an abutment facing the said 30 aperture, the outer end portion of the seal being formed as a stop engaging said abutment to prevent withdrawal of the strip from the aperture, means on the mount adapted to prevent transverse displacement 35 of the strip, and the portion of said strip between the aperture and the abutment being weakened to insure breakage of such portion if bent.

5. In combination with a receptacle having a body member and a cover member lapping each other for closure, a seal lock 40 comprising a mount extending from the outer one of said members, an aperture being provided for access to the inner member, 45 said mount having an abutment facing the aperture, and a seal strip having one end adapted to be inserted in said aperture for engaging the inner member, the outer end of the seal strip being folded back toward 50 the inner end which is thus inserted in the aperture, and the portion of said strip between such fold and the outer end engaging the abutment of the mount to prevent withdrawal of the strip from the aperture.

55 6. A seal lock comprising in combination

with a seal mount which has a web and an inner and an outer abutment extending across the web at a distance apart therealong, and cut away to leave a clear path for a seal entering along the web, the web 60 being cut away opposite the outer abutment; a seal bolt comprising a strip doubled upon itself, one ply being extended beyond the other, its length from the fold to the more remote ply end being sufficient for extending past both abutments at once, and being so weakened at a transverse line which stands adjacent to the outer edge of the web when the seal is engaged past both abutments, that when folded at said weakened 70 line back away from the outer abutment to carry the other ply to a position projecting past said outer abutment at the inner side thereof, it cannot be straightened without breaking at said folded line. 75

7. A seal lock comprising in combination with a seal mount which has a web and an inner and an outer abutment extending across the web at a distance apart therealong, and cut away to leave a clear path 80 for a seal entering along the web, the web being cut away opposite the outer abutment; a seal bolt adapted to be entered along the seal path, of sufficient length to extend past both abutments at once, and weakened 85 at a transverse line which stands adjacent to the outer edge of the web when the bolt is engaged past both abutments, said seal bolt having a terminal positioned intermediate said weakened line, and the inner end 90 of the bolt, and extending from a point on the seal bolt located at the opposite side of said weakened line from the inner end of the bolt, whereby when said seal bolt is folded at said weakened line, back away from the 95 outer abutment over the outer edge of the web, said terminal is carried up to a position projecting across said outer abutment at the inner side thereof, the weakening being such that the seal cannot be straightened without breaking at said weakened 100 line.

In testimony whereof, I have hereunto set my hand at Chicago, Illinois, this 8th day of May, 1914.

EMIL TYDEN.
